UNITED STATES PATENT OFFICE.

IRA J. SAUNDERS, OF LYNN, MASSACHUSETTS.

BUTTON-ATTACHING MACHINE.

SPECIFICATION forming part of Letters Patent No. 371,632, dated October 18, 1887.

Application filed February 14, 1887. Serial No. 227,514. (No model.)

To all whom it may concern:

Be it known that I, IRA J. SAUNDERS, of Lynn, in the county of Essex and State of Massachusetts, have invented certain new and 5 useful Improvements in Machines for Attaching Buttons, of which the following, taken in connection with the accompanying drawings, is a specification.

My invention relates to that class of button-10 attaching machines in which the buttons and the fastenings are automatically fed to the position for setting the fastening, and is an improvement upon the invention described in Letters Patent No. 344,220, granted to me as 15 the assignee of Eugene H. Taylor, June 22, 1886; and it consists in certain novel features of construction, arrangement, and combination of parts, which will be readily understood by reference to the description of the 20 drawings, and to the claims to be hereinafter given.

Figure 1 of the drawings is a sectional elevation of so much of my improved machine as is necessary to properly illustrate my invention. Fig. 2 is a front elevation of portions of 25 the same parts. Fig. 3 is a side elevation of portions of the same parts, and Fig. 4 is a transverse section of the driver-stock raceway and the cam-plate for moving the driver laterally.

In the drawings, A is the frame of the head 30 of the machine, consisting of a hollow column provided with the laterally-projecting anvil-support *a*, the arms *b* and *b'*, in which are formed bearings for the reciprocating driver-stock or plunger *c*, and the curved arm *d*, all constructed and arranged substantially as shown and described in said Letters Patent No. 344,220.

40 B is a rotatable cylinder having upon its exterior a series of vertical raceways or grooves, *e*, each adapted to receive a series of button-fasteners with buttons attached, as shown and described in said prior patent.

45 C is a lever having its fulcrum on the pin *f* set in the curved arm *d*, and having connected thereto, at or near the middle of its length, the rod *D*, the lower end of which is connected to a treadle-lever mounted upon a fulcrum-pin *D'*, set in the lower portion of a supporting-column, said rod *D* being provided with a spiral 50 spring, *D'*, within the frame A, for moving said

rod, the lever C, and the cylinder B upward, said spring resting at its lower end upon an abutment in the form of a plate supported by 55 the upper end of the supporting column, and acting at its upper end against a collar, *g*, secured upon the rod D, all as shown in dotted lines in Fig. 1, and as shown and described in the above-mentioned Letters Patent. 60

To the front end of the lever C is pivoted the upper end of the driver-stock *c*, mounted in bearings in the arms *b* and *b'*, and provided near its lower end with the offset *h*, to which is firmly secured the steel driver *h'*, as shown 65 in Fig. 1.

The cylinder B is mounted upon the spindle or short vertical shaft E, having a bearing in the hub at the end of the curved arm *d*, and upon which is firmly secured the cylinder-supporting disk or rim F, provided at one side with the pendent ear *i*, to which is secured the upper end of the plate H, which in turn is secured to the front ends of the arms *b* and *b'* by means of the screws *j*, which pass through 70 slots *k*, formed in said plate, and screw into said arms, as shown in Fig. 2.

The plate H has formed therein the vertical slot or groove *l*, of the form shown in Fig. 4, the upper end of which coincides with the 75 lower end of one of the correspondingly-shaped grooves *e*, formed in the periphery of the cylinder B, when properly set and locked, which is done as described in the Letters Patent hereinbefore referred to. 80

The groove *l* in the plate H serves as a guide or raceway to direct the fasteners with buttons attached to a position in close proximity to the material in which they are to be set.

The spindle E rests at its lower end upon 90 the boss *m*, formed upon the lever C, and when the lever C is moved upward by the action of the spring within the frame A the cylinder B, disk or rim F, and raceway H *l* are moved upward too, and maintained in the position shown 95 in Fig. 1, or with the lower end of the raceway H *l* raised about one-quarter of an inch above the upper surface of the anvil *n*, firmly secured upon the supporting arm *a* in a position directly beneath the raceway, as shown.

100 A slot, *o*, is cut through the back of the raceway H *l*, near its lower end, to permit a lateral movement of the driver *h'* and the offset portion of the driver-stock *c* through

the same, so that the driver h' as it descends may be moved into the groove l and descend therein directly upon the button-fastener and drive it into the material placed upon the anvil n , and as it ascends said driver may be retracted from said groove, so as to permit a free passage of the fastener with the button attached down said raceway to a point near its lower end. This lateral movement of the driver is obtained by means of the anti-friction roll p , mounted upon a stud, p' , set in the side of the driver-stock c and projecting into the curved cam-slot q , formed in the plate I , secured in a fixed position upon the sides of the arms b and b' , as shown in Figs. 2, 3, and 4.

The downward movement of the column of buttons in the raceway $H l$ and the groove e in the cylinder B , which for the time being is set to coincide with said raceway, is arrested by the curved lever r , the free end of which bears against the front face of the plate H when the driver, the raceway, and the cylinder are at the extreme of their upward movements, as shown in Fig. 3.

Another curved lever, r' , located below the lever r , with its free end upward, is connected to said lever r by the spring s , said levers r and r' being provided, respectively, with a rearwardly-projecting straight arm, r^2 and r^3 , the construction, arrangement, and operation of said levers r^2 and r^3 being the same as described in the Letters Patent hereinbefore referred to.

The lever r' is moved outward by the action of the pin s' upon the arm r^3 during the last part of the upward movement of the driver-stock c , in which said pin is set.

When the driver-stock begins to descend, the lever r' begins to move inward and continues to move until its free end comes in contact with the front of the raceway, at which time the pin s^2 , set in the lever C , has come in contact with the arm r^2 and commenced to move the free end of the lever r outward to release the column of buttons and allow them to descend till arrested by the lever r' , all substantially the same as described in said prior patent.

In said prior patent the button and fastener to be set were received at the end of the raceway in a carrier the groove in which had side walls that approached each other at its lower end nearer than at its upper end, for the purpose of preventing the fastener dropping through said carrier before the carrier reached a position beneath the driver and in contact with the material resting upon the anvil. In this case the raceway has parallel sides, through the whole length of which the button-fastener, with its button attached, may drop freely, unless arrested in its course by some means outside of said raceway—such, for instance, as the levers r and r' .

To arrest the single fastener and its attached button at or near the end of the raceway in position to be acted upon by the driver in its descent, I secure to the front of the raceway a third curved elbow-lever, t , with its curved

free end downward and its straight rearwardly-projecting arm, t' connected by the link t^2 to the arm r^3 , as shown in Figs. 2 and 3.

The operation of my invention is as follows: The several parts being in the positions shown in the drawings, with a button supported by the lever t near the end of the raceway and a column of buttons in the raceway above the lever r , the operator places the material in which the fastener is to be set upon the anvil n , between it and the end of the raceway $H l$, and places his foot upon the treadle (not shown) and presses downward thereon, to compress the spring within the column of the frame A and move the front end of the lever C and the driver h' and driver-stock c downward. When the lever C moves downward, the cylinder B and raceway $H l$ and disk or rim F are all moved downward by the force of gravity until the end of the raceway rests upon the material placed upon the anvil. The first part of the downward movement of the driver-stock causes said stock and its driver to be moved laterally till the driver h' is in a vertical position in the center of the groove l and directly over the fastener in said groove, near the end of the raceway, said driver-stock pivoting about a point in line with the upper edge of its bearing in the arm b' . When the lower end of the raceway $H l$ comes in contact with the material placed upon the anvil n , the downward movement of said raceway, the disk or rim F , and the cylinder B is arrested, while the continued downward movement of the driver h' forces the prongs of the fastener through the material against the anvil, by which they are clinched in a well-known manner. During the first part of the downward motion of the driver-stock c the descent of the pin s' permits the lever r^3 to move about its axis till the free end of the arm r' thereof comes in contact with the front face of the raceway, at which time the free end of the lever r is moved outward or away from the raceway by the downward movement of the pin s^2 acting upon the arm r^2 of said lever, thereby permitting the column of buttons above said lever to descend till the lower button comes in contact with the lever r' .

When the operator removes his foot from the treadle, the reaction of the spring on the rod D causes the rod D , lever C , driver-stock c , raceway $H l$, disk or rim F , and the cylinder B to be moved upward to the positions shown in the drawings. The upward movement of the driver-stock c and the pins s' and s^2 first permits the levers r and t to be moved about their axis by the reaction of the spring s until the free ends of said levers come in contact with the front face of the raceway and the end of the lever r has been interposed between the lower button in the column in the raceway above the lever r' and those above it, when the pin s^2 comes in contact with the arm r^3 of the lever r' and causes the free end of said lever r' to be moved away from the raceway, thereby permitting the single button held thereby to descend the raceway.

until arrested by the lever t in position to be set at the next descent of the driver.

What I claim as new, and desire to secure by Letters Patent of the United States, is—

5 1. In a machine for attaching buttons, a straight vertical and vertically-movable raceway having a T-shaped cross-section and adapted to receive and guide a column of staple-fasteners and their attached buttons, in combination with a fixed anvil located directly beneath said raceway, a reciprocating driver arranged in close proximity to said raceway, and parallel, or nearly so, therewith, and provided with an anti-friction roll mounted upon 10 a laterally-projecting stud set therein, and a fixed cam constructed and adapted to move the lower end of said driver laterally into and out of said raceway, and means, substantially as described, for moving said raceway vertically, substantially as and for the purposes described.

15 2. The combination, in a machine for attaching buttons, of the vertical staple-raceway H l , having the slot o cut through its back side near its lower end, the vertically-reciprocating driver-stock c , provided with the offset h , the driver h' , secured to the front face of said offset portion of the driver-stock, the anti-friction roll p , carried by said driver-stock, the 20 fixed plate I , provided with the cam-slot q , and the fixed anvil n , located directly beneath said raceway, all constructed, arranged, and adapted to operate substantially as and for the purposes described.

25 3. In a button-attaching machine, the combination of a fixed anvil, a straight vertical staple-raceway arranged directly over said anvil and rigidly attached to a cylinder-supporting disk or rim firmly secured upon a vertically-movable spindle having a bearing in the frame of the machine, a rotatable cylinder mounted upon said disk or rim and provided upon its exterior with a series of grooves corresponding in shape and size in cross-section to the groove in said raceway, and adapted to be brought successively into position over and in line with said raceway, and means, substantially as described, for moving said raceway, disk or rim, and cylinder vertically, for 30 the purposes described.

40 4. In combination with a fixed anvil, a straight vertical staple-raceway, the groove in which is of the same width throughout its entire length and movable vertically to and from said anvil, a vertically-reciprocating and laterally-moving driver and stock, an inter-

mittently-vibrating elbow-lever constructed and arranged to be moved about its axis in one direction by the descent of said driver and its stock and in the other direction by a spring, 60 and arranged to be operated substantially as described, to arrest the descent of a button and its staple at or near the lower end of said raceway when the raceway is at or near the extreme of its upward movement, and to release said button again when said raceway is in contact with the anvil or the material resting thereon, and in time to be moved by the driver during the last part of its downward movement, substantially as described. 65

5. The combination of the fixed anvil n , the straight vertical raceway H l , having a groove of uniform width throughout its entire length and movable vertically to and from said anvil, the vertically-reciprocating and laterally-movable driver and stock h c , the elbow-levers r r' , r'' r''' , and t t' , the link t' , connecting the arms r^2 and t' , the spring s , connecting the arms r and r' , and the pins s' and s'' , constructed and arranged to be moved vertically in unison 70 with the driver and to act upon the arms r^2 and r''' , substantially as described.

6. In a machine for attaching buttons, a straight vertical and vertically-movable raceway having a T-shaped cross-section, and adapted to receive and guide a column of staple-fasteners and their attached button, in combination with an anvil located directly beneath said raceway, a vertically-reciprocating and laterally-movable driver arranged parallel, 85 or nearly so, to said raceway, a cam for moving said driver laterally, and mechanism, substantially as described, for reciprocating said driver and moving said raceway vertically, as and for the purposes described. 90

7. The combination of the straight vertical raceway H l , the disk or rim F , the cylinder B , and the spindle E , all mounted and movable vertically together upon the frame A , with the driver and stock h c , a cam for moving said driver and stock laterally, the lever C , the treadle-operated rod D , and the spring D' , all constructed, arranged, and adapted to operate substantially as and for the purposes described. 95

In testimony whereof I have signed my name to this specification, in the presence of two subscribing witnesses, on this 5th day of February, A. D. 1887.

IRA J. SAUNDERS.
